US0D1009262S

(12) **United States Design Patent** (10) **Patent No.:** **US D1,009,262 S**
(45) **Date of Patent:** **** Dec. 26, 2023**

(54) **VIDEO PROCESSING APPARATUS**

- (71) Applicant: **AMBU A/S**, Ballerup (DK)
- (72) Inventors: **Line Ubbesen**, Holte (DK); **Scott Peter Allen**, Frederiksberg (DK); **Nai-Hua Chen**, Kaohsiung (TW)
- (73) Assignee: **AMBU A/S**, Ballerup (DK)
- (**) Term: **15 Years**
- (21) Appl. No.: **29/890,227**
- (22) Filed: **Apr. 21, 2023**

Related U.S. Application Data

(57) **CLAIM**

The ornamental design for a video processing apparatus, as shown and described.

DESCRIPTION

FIG. 1 is a top, front perspective view of a video processing apparatus showing our new design in a first embodiment; FIG. 2 is a front view thereof; FIG. 3 is a rear view thereof; FIG. 4 is a left side view thereof; FIG. 5 is a right side view thereof; FIG. 6 is a top view thereof; and FIG. 7 is a bottom view thereof.

FIG. 8 is a top, front perspective view of a video processing apparatus showing our new design in a second embodiment; FIG. 9 is a front view thereof; FIG. 10 is a rear view thereof; FIG. 11 is a left side view thereof; FIG. 12 is a right side view thereof; FIG. 13 is a top view thereof; and, FIG. 14 is a bottom view thereof.

Uniformly-sized broken lines illustrate portions of the video processing apparatus that form no part of the claimed design. Long-short broken lines illustrate boundaries of the claim and form no part of the claimed design.

1 Claim, 14 Drawing Sheets
